UNITED STATES PATENT OFFICE

BENJAMIN GROSS, OF NEW YORK, N. Y.

DESIGN FOR A FINGER RING OR SIMILAR ARTICLE

Application filed September 8, 1932. Serial No. 44,778. Term of patent 3½ years.

To all whom it may concern:

Be it known that I, BENJAMIN GROSS, a citizen of the United States, residing in New York, in the county and State of New York, have invented a new, original, and ornamental Design for a Finger Ring or Similar Article, of which the following is a specification, reference being had to the accompanying drawing, forming a part thereof.

Fig. 2 is a face elevational view thereof.

Fig. 3 is a sectional view thereof taken on lines 3—3 of Figure 2.

I claim:

The ornamental design for a finger ring, or similar article, as shown.

In testimony whereof, I affix my signature.

BENJAMIN GROSS.
